UNITED STATES PATENT OFFICE.

VINCENT G. APPLE, OF DAYTON, OHIO, ASSIGNOR TO THE APPLE ELECTRIC COMPANY,
OF DAYTON, OHIO, A CORPORATION OF OHIO.

SWITCH.

1,189,900.

Specification of Letters Patent.

Patented July 4, 1916.

Application filed August 17, 1914. Serial No. 857,079.

To all whom it may concern:

Be it known that I, VINCENT G. APPLE, a citizen of the United States, residing at Dayton, in the county of Montgomery and State of Ohio, have invented certain new and useful Improvements in Switches, of which the following is a specification.

This invention relates to improvements in electric lighting apparatus for automobiles and more particularly to a switch and wiring system whereby various combinations of lights may be connected with the battery or other source of energy.

One of the objects of my invention is to provide a simple, compact and efficient switch together with its wiring connections whereby the lights, in different combinations, may be connected with said source of electric energy, and the head lights dimmed when desired by connecting them in series, thus lowering their individual voltage and consequently reducing their candle power.

Another object of my invention is to provide such an apparatus in which the tail light must always be lighted when any other of the lights such as the side lights or head lights are being used.

Still another object of my invention is to provide contacts and movable switch arms so constructed as to of themselves provide stops for positioning the switch blades in their various operative positions.

Other and further objects will become apparent to those skilled in the art from a consideration of the following description and drawing, wherein—

Figure 1 is a horizontal cross section through the dash board or instrument board of an automobile showing the method of mounting my improved switch. Fig. 2 is a front elevation of said dash board showing the parts visible to the operator. Fig. 3 is a horizontal diametrical sectional view through my improved switch. Fig. 4 is a sectional view on the line 4—4 of Fig. 3, the wiring being indicated diagrammatically. Fig. 5 is a sectional view on the line 5—5 of Fig. 4. Fig. 6 is an elevation of the rear face of the switch with the wiring indicated diagrammatically. Fig. 7 is an elevation, with parts broken away, of a modified form of switch adapted for use with two head lights, two side lights and tail light. Fig. 8 is a sectional view on

the line 8—8 of Fig. 7, and; Fig. 9 is an elevation of the rear face of the switch shown in Fig. 7 with the wiring indicated diagrammatically.

In all the views the same reference characters indicate like parts.

Referring to the form of switch illustrated in Figs. 1 to 6 inclusive it will be noted that the switch containing part or body part is of generally cylindrical form comprising a disk like base 10 having at its periphery an outwardly extending flange or rim 11 forming a cup shaped body inclosing a chamber 12 in which the movable switch parts are contained. Two lugs 13 and 14 extend outwardly from the rim 11 at diametrically opposite points and provide means for securing the switch to the rear face of an instrument board 15. Two internally tapped cylinders 16 extend through the lugs 13 and 14 and at their forward ends pass through openings in a bridge plate 17. The rear end of the tubes 16 are headed as at 18 and at their opposite ends they are flanged over thus making rigid connection with the bridge plate 17. The connecting screws 18' pass through the front face of the instrument board 15 into the tapped opening in the tubes 16 and hold the switch in position. At the front face of the instrument board 15 I have provided a dial or plate 19 through which the screws 18 pass. The particular switch illustrated in Figs. 1 to 6 is adapted for use with a head light tail light outfit and the dial therefore indicates "off", "on", and "dim".

I prefer to make the body part of the switch of fiber, bakelite or similar insulating material which is easily molded and forms a substantial body into which the binding posts and contacts may be secured.

A threaded sleeve 20 extends through the base part 10 at its center and carries at its inner end a bearing pin 21 of reduced diameter which extends into the cup opening 12 and serves as a bearing upon which the switch post 22 is pivoted. The switch post passes through an opening in the center of the bridge plate 17 and is provided with a flange 23 which underlies the inner surface of the plate 17 securely holding the post in place. Two switch arms are carried by the post 22, the one indicated by the numeral 24 being positioned directly at the rear of the flange 23 and making close contact there-

with. Directly beyond the flange 23 is placed a fiber washer 25 upon which rests the second switch arm 26. The opening in the switch arm 26 is considerably larger than that of the pin and receives an insulating bushing carried by the washer 27. A nut 28 is threaded on the inner end of the switch post and holds the arm in rigid position thereon. The two switch arms 24 and 10 26 are disposed at approximately 90 degrees to each other and carry on their end the button shaped contact points 29. The outer end of the switch post 22 carries a transverse pin 30 for engagement with the slot 15 31 of the tubular operating key 32. The outer end of the key 32 is provided with an arrow shaped head 33 which registers with the indications on the dial face 19. When the key is removed the switch is locked in 20 the desired position and nothing projects beyond the face of the dial.

Four switch contacts indicated in general by B-, B+, H, and C are positioned in the base 10 at approximately 90 degrees to each 25 other. The construction of the contacts is illustrated in detail in Fig. 5. Each comprises a tubular insert 34 fitting tightly within an opening in the base and centrally tapped to receive the contact screws 35. The 30 inner end of the tube 34 is beveled out as at 36 to receive the buttons 29 on the switch arms. Two other contact pins indicated in general by letters M and N are positioned diametrically opposite each other and 35 comprise solid pins 37 cup shaped at their inner ends 38. A screw terminal T is threaded into a tapped opening in the sleeve 20 and serves as a fifth binding post. A short strip of metal 39 joins the two contacts H and M 40 and a second arcuate strip 40 joins the two contacts B+ and N.

In Fig. 4 the switch is positioned with its switch blades intermediate the contacts and a slight movement or rotation of the post to 45 the left will throw the ends of switch blade 24 onto contacts M and N, and at the same time the ends of switch blade 26 will drop into depressions 41 and 42 cut in the insulating material. This is the extreme left 50 hand position, the right hand end of the switch blade 26 making contact with a post 43 of insulating material carried in the wall 11 of the base part. When in this position the tail light is lighted and the head lights 55 dimmed. When the switch blades are rotated slightly to the right of the position indicated in Fig. 4 the ends of switch blade 24 will drop into the depressions 44 and 45 cut in the insulating material of the base. 60 At the same time the ends of switch blade 26 will drop into the depressions 46 and 47 in the insulating material and at this point the switch is in the off or neutral position. A further rotation to the right carries the 65 ends of the switch blade 24 against contacts

C and B+, the ends of the switch blade 26 making contact with contacts H and B-. The upper end of the switch blade 24 in this position makes contact with the insulating stop post 43. The switch is then 70 positioned so that the head lights and the tail light will receive full battery voltage.

The wiring terminals on the switch are all positioned at the rear face thereof for ready access. In connecting up the switch in the 75 lighting circuit of an automobile the positive terminal of the battery A is connected by wire 48 to terminal B+, and the negative terminal of the battery is connected by a wire 49 with terminal B-. One side of the 80 tail light TL is connected by wire 50 with terminal T and the other side connected by wire 51 to wire 49 at point 52. One side of each of the head lights HL and H'L' are joined by wire 53, the opposite terminal of head light H'L' being connected with wire 54 the other end of which is connected with wire 49 at point 52. The opposite terminal of the head light HL is joined by wire 55 to terminal H. A feed wire 56 extends from terminal C to point 57 on wire 53.

With the switch in the central or "off" position all four contact points on the switch blades rest in depressions in the insulating base 10 and no current flows from the battery to any of the lights. Rotating the switch post to the right to the "on" position throws switch blade 24 across terminals C, B+ and switch blade 26 across terminals B-, H. Current will then flow from the positive terminal of the battery A through wire 48 to terminal B+ across switch blade 24 to terminal C, thence on wire 56 to wire 53, leading to each of the head lights. The return from head light 100 HL is through wire 54 to point 52, thence to the negative side of the battery. The return from headlight H'L' is over wire 55, terminal H, across switch blade 26 to terminal B-, over wire 49 to point 52 and to the 110 negative side of the battery. The head lights are thus connected in parallel each to receive full battery voltage. At the same time current flows from the positive side of the battery to the switch blade 24, out 115 through terminal T, over wire 50 to one side of the tail light from which it returns over wire 51 to point 52 and to the negative side of the battery.

To dim or reduce the candle power of 120 the head lights, the switch post is rotated to its extreme left position with switch blade 24 bridging terminals M, N and the ends of switch blade 26 resting in the depressions 41, 42. With the switch blades in these 125 positions, current will flow from the positive side of the battery A, over wire 48, to terminal B+, thence over strip 40, to terminal N across switch blade 24 to terminal M, across strip 39 to terminal H, through 130

wire 55 to one side of head light $H'L'$ direct over wire 53 to one side of head light HL and returning through wire 54 to point 52 on wire 49 and into the negative side of the battery. As in the previous case, the tail light TL is connected by wire 50 on one side to the terminal T which contacts with switch blade 24 and on the other side through wire 51 to the negative side of the battery. While in this position the two head lights are in series with each other across the battery and their candle power thus materially decreased, the tail light, however, receiving full battery voltage.

In the embodiment of my invention illustrated in Figs. 7, 8 and 9 I have shown a switch adapted for use in connection with a head light, side light and tail light outfit, there being five positions of the switch. The first position at the extreme left is with the head lights dim and the tail light lighted. The second position from the left is with both head lights and tail light on full voltage. The next position, or central position, is with all lights extinguished. The next position to the right is with full current flowing to head lights, side lights and tail light. The extreme position to the right or the fifth position is with the side lights and tail light receiving full voltage, the head lights being extinguished. The construction of this switch is substantially similar to that illustrated in Figs. 1 to 6 and I have indicated the corresponding parts with the same numerals adding a prime mark (') thereto. The switch blades 24' and 26' instead of being positioned at 90 degrees to each other are at an acute angle, somewhat less than 45 degrees and the insulated switch blade 26' is considerably shorter than the switch blade 24', its end contacts rotating in a different circle and upon different contact points. It will be noted from Fig. 9 that four terminals, $B'+$, S' , C' and H' are positioned in the outer circle receiving current from the switch blade 24' whereas the terminal $B'-$ is in the inner circle receiving current from switch blade 26', the central terminal T' being positioned as in the other switch centrally and in contact with the switch post.

The wires leading from the head lights, tail light and battery to the switch are positioned as in the previously described system and I have therefore indicated the wires by the same numerals with the added exponent. The side lights SL and $S'L'$ are paralleled by the two wires 60 and 61, feed wire 62 extending from the main wire 60 to wire 51' and the second feed wire 63 extending from the main wire 61 to terminal S' .

The inner construction of the switch is illustrated in Fig. 7. In the upper sector four outer circle contacts $B'+$, 64, 65 and

66 are provided, all electrically connected by means of the arcuate metallic strip 67. In the lower sector the two terminals C' and 68 are joined by an arcuate metallic strip 69. At the left of the terminal 68 is another terminal S' , from which extends a leaf spring or contact 70, extending over the terminal 68 so that when the lower arm of switch blade 24' is positioned on terminal 68 the leaf 70 contacts with its upper surface making electrical connection therefor with terminal S' . In the upper sector two inner contacts $B'-$ and 71 are provided for engagement with the switch blade 26. These are joined by an arcuate metallic strip 72. An opposite pair of terminals 73, 74 are positioned in the lower sector and likewise are joined by a metallic strip 75, the terminal 73 being joined to terminal H' by strip 76.

When the switch is in the position illustrated in Fig. 7, the opposite ends of switch blade 24' rest in depressions 77, 78 in the insulating material and the ends of the switch blade 26' rest in similar depressions 79, 80. When in this position all lights are extinguished. When the switch is rotated one point to the right of the zero position, switch blade 24' bridges terminals 68 and 65 whereas switch blade 26' bridges terminal $B'-$ and 74. When in this position current flows from the battery direct to each head light with full voltage and to the tail light as previously described. In addition to this the side lights are supplied with current, at full voltage.

When the switch is rotated from zero to the left one point, the switch blade 24' bridges terminals 64 and C' , whereas switch blade 26' bridges terminals 71, 73. When in this position both head lights and tail light are supplied with full voltage and the side lights are not in circuit. When the switch is rotated from this position still further to the left, switch blade 24' bridges terminals $B'+$ and H' and the ends of switch blade 26' rest in depressions in the insulating base. In this position the head lights are connected in series and therefore are dimmed and the tail light is given full voltage.

When the switch is rotated to the extreme right position, the side lights and tail light alone are supplied with current, the switch blade 24' bridging terminals 66, S' and 120 switch blade 26' resting in depressions 81, 82 in the insulating base.

Having described my invention, what I claim is:

1. The combination in a switch of a blade movable in the plane parallel to one wall of the casing and having convex projections thereon, a contact for said blade adapted to be engaged by said convex projections and comprising a metallic member having a

through aperture, the inner end of which is impositively engaged by the convex projection on the switch blade, said aperture being threaded at its outer end and a terminal screw taking into said threaded aperture.

5 2. A switch comprising a body part of insulating material, a switch blade movable in a plane parallel to one wall of the casing and having button shaped projections on the ends thereof, contacts for said blade comprising internally threaded tubes positioned in the wall of said casing substantially parallel to the switch blade with their inner ends flush with the inner surface of the wall, and terminal screws taking into said threaded tubes from their outer ends.

10 3. A switch comprising a cup shaped body part of insulating material, a concentrically positioned rotatable metallic post extending within the cup and having an opening in its inner end, a metallic pin carried at the center of the body part and projecting into said opening to provide a journal for said post, a terminal screw engaging the outer 15 end of the pin, a switch blade mounted on the post within the confines of the body 20 part of insulating material, a concentrically positioned rotatable metallic post extending within the cup and having an opening in its inner end, a metallic pin carried at the center of the body part and projecting into said opening to provide a journal for said post, a terminal screw engaging the outer 25 end of the pin, a switch blade mounted on the post within the confines of the body

part, and contacts carried in the body part for engagement by said blade.

4. A switch comprising a cup shaped body part of insulating material, a concentrically positioned rotatable metallic post extending within the cup and having an opening in its inner end, a metallic pin carried at the center of the body part and projecting into said opening to provide a journal for said post, a terminal screw engaging the outer end of the pin, a switch blade mounted on the post within the confines of the body part, contacts carried in the body part for engagement by said blade, a collar formed on the post, a cross bar having a perforation through which the post extends overlying said collar and means for securing the ends of the cross bar to the rim of said cup shaped body part.

45 In testimony whereof I hereunto set my hand in the presence of two subscribing witnesses.

VINCENT G. APPLE.
